CLAIM

The ornamental design for a lunch bag, as shown and described.

DESCRIPTION

FIG. 1 is a perspective view of a lunch bag, showing my new design.

FIG. 2 is a front view of a lunch bag.

FIG. 3 is a rear view of a lunch bag.

FIG. 4 is a left side view of a lunch bag.

FIG. 5 is a right side view of a lunch bag.

FIG. 6 is a top view of a lunch bag; and,

FIG. 7 is a bottom view of a lunch bag.

The broken lines representing stitching are part of the claimed design.

The broken lines oval shape in FIGS. 1 and 2 and the broken lines hardware detail in FIG. 4 are for showing portions of the lunch bag only and form no part of the claimed design.
